UNITED STATES PATENT OFFICE.

EDGAR M. NORTH, OF BROOKLYN, NEW YORK.

ELECTRIC BLOCK-SIGNAL.

SPECIFICATION forming part of Letters Patent No. 714,734, dated December 2, 1902.

Application filed March 22, 1902. Serial No. 99,429. (No model.)

To all whom it may concern:

Be it known that I, EDGAR M. NORTH, a citizen of the United States, residing at Brooklyn, in the county of Kings and State of New York, have invented certain new and useful Improvements in Electric Block-Signals; and I do hereby declare the following to be a full, clear, and exact description of the invention, such as will enable others skilled in the art to which it appertains to make and use the same.

My invention has relation to automatic signals designed, primarily, as a block-signal system for railways; and it consists of certain novel features of combination and construction of parts, the preferred form whereof will be hereinafter fully described, illustrated, and pointed out in the claim.

The object of my invention is to provide an electrically-actuated system of coöperating parts initially set into motion by mechanical appliances, as the flange of a wheel of an electric car or railway-train.

A further object is to insure that if one car or train follows too closely upon another the motorman or engineer in the following car or train will be instantly and unerringly informed that he is upon the closed block of the preceding train, such information being communicated to the man in charge by any of the well-known devices, as a red light placed at a convenient point or the ringing of a warning-bell.

Other objects and advantages will be fully apparent from the following specification, which must be considered in connection with the accompanying drawings, in which—

Figure 1 illustrates a portion of an ordinary electric car provided with a depending brush, as is common, and also showing a contact-rail properly insulated and duly located near the trackway to be contacted by said brush. Fig. 2 is a top plan view of a section of a track, showing a block or portion of the track provided with my automatic signaling devices. Fig. 3 is a detail view, partly in section, of part of my invention, showing manner of closing a portion of the electric circuits, while Fig. 4 is a similar view of other coöperating parts.

In order to conveniently designate the several features of my invention and coöperating accessories, numerals will be employed, of which 1 is a shoe or brush properly insulated

in any of the well-known ways and suspended from a car or locomotive, said shoe or brush being designed to contact with the insulated terminal 2, which is mounted at a proper height adjacent to the trackway, as upon the insulating-standards 3, so as to be in position to be contacted by the brush 1. The insulated section or terminal 2 is connected, as by the wire 4, with electrical and mechanical devices, (illustrated in Fig. 3,) the continuation of the wire 4 being designated by the numeral 5. At the first end of the block or track-section to be protected by my electrical appliances I locate the housing 6, mounted upon the support or standard 7 and having within said housing the bracket 8, to which I pivotally secure the lever 9, having upon its outer end the semaphore-like terminal 10 and upon its inner end the beveled edge 11, which latter is designed to engage the armature-pawl 12, pivoted in position upon a suitable support, as indicated by the numeral 13, said pawl being designed to be controlled by the magnet 14, as will be hereinafter more particularly pointed out. I pivotally connect the lever 9 with the outer end of the lever 15, which is properly mounted in position (preferably below the surface of the trackway) by means of the link-section 16. The lever 15 extends under the trackway and has pivoted thereto the vertically-disposed pin 17, which is held in its operative position by means of the bracket 18 and is designed to be engaged by the flange of the wheel and forced downward, thereby causing the lever 9 to be bodily elevated or moved upon its pivot-point and bring the beveled end thereof under the hook-terminal of the armature-pawl. When the lever 9 has been elevated into the position occupied by the dotted lines in Fig. 3, it will cause the elevation of the pins 19 and 20, both of which are held normally downward by means of the coiled spring 21, as clearly shown. When the pins 19 and 20 are thus elevated, each will engage its respective contact-point or terminal 22 and 23, said contacts being respectively provided with the wires 24 and 25. The elevation of the pins will thus close the circuit between the wires 5 and 25 and also the circuit represented by the wires 24 and 26.

It will be observed that the wire 25 is in connection with the battery or other source of

electrical energy, inasmuch as batteries or 5 dynamos may be employed, as desired. The wire 5 extends into engagement with the rail-terminal or contact-point 2, as hereinbefore stated. It is therefore obvious that when the circuit is closed between the wires 5 and 25 the terminal 2 becomes energized or electrically charged, and if therefore a second train should come upon this end of the block 10 or track-section the brush 1, being connected with a light or bell in the car, the motorman will thereby cause a warning placed in view or sound of the engineer or motorman and he will thereby know that he is too closely 15 following the preceding train or car and should stop or check his speed accordingly.

At the last end of the block or track-section covered by my automatic signaling system I place the devices illustrated in Fig. 4, 20 comprising the lever 27, properly disposed similarly to the lever 15 below the surface of the trackway and pivoted upon the bolt 28 and provided at its inner end with the vertically-disposed pin 29, held in position by the bracket 30, so as to be in the path of the flange 25 of the wheel. The outer end of the lever 27 may be provided with a semaphore 31 and is also provided with an insulated contact-point 32, which is in connection with the contact-point 22 by means of the wire 24. I also provide upon the block 33 the insulated contact-point 34, placed in electrical connection with the contact-point 23 by means of the wire 25, and it is therefore obvious that when the flange of the 35 wheel engages a pin 29 the outer end of the lever 27 will be elevated, causing the contact-point 32 to engage the contact-point 34, and thereby close the circuit of the wires 23 and 25. When the electrical contact is thus completed 40 between the points 32 and 34, the current passes from wire 25 through 24 and 26 to the electromagnet 14, thereby energizing said magnet and causing it to drag the upper free end of the armature-pawl 12 and draw 45 the hook-terminal thereof out of engagement

with the beveled end 11, thus releasing the lever 9, which reassumes the position shown in full lines in Fig. 3, and thus breaking electrical connections between the points 19 and 20 and the contact-points 22 and 23. 50

It will of course be understood that if preferred the current may be switched on and off of the contact-rail 2 manually, though the means herein illustrated and described will be found perfectly automatic and reliable in 55 the performance of their office. It will be further obvious that various mechanical or electrical substitutes and equivalents may be adopted in carrying out my invention, and I therefore wish to comprehend all such substitutes and equivalents as fairly fall within the 60 scope of my invention, my aim being to provide means for protecting any car or train while upon a block or track-section covered and controlled by my appliance, substantially 65 as herein illustrated and described.

Having thus fully described my invention, what I claim as new, and desire to secure by Letters Patent, is—

The herein-described block-signal, comprising 70 an insulated terminal or rail-section 2 adjacent to the trackway; a brush depending from the car and adapted to engage said terminal; a semaphore-lever pivotally mounted at the initial end of the block; suitable means 75 to place said lever in the control of the passing wheel whereby the lever will be elevated; an armature having a hook adapted to secure said lever in an elevated position; suitable electric circuits; means coöperating with said 80 lever to close said circuits when the latter is raised; an electric magnet coöperating with said armature, all substantially as specified and for the purpose set forth.

In testimony whereof I affix my signature 85 in presence of two witnesses.

EDGAR M. NORTH.
